US00D993261S

(12) **United States Design Patent** (10) **Patent No.:** **US D993,261 S**
Hernandez (45) **Date of Patent:** **** Jul. 25, 2023**

(54) **CRYPTOCURRENCY PASSWORD
NOTEBOOK PAGE**

(71) Applicant: **Shieldfolio Inc.**, Temple City, CA (US)

(72) Inventor: **Jose Alfredo Hernandez**, Temple City, CA (US)

(73) Assignee: **Shieldfolio Inc.**, Temple City, CA (US)

(**) Term: **15 Years**

(21) Appl. No.: **29/804,178**

(22) Filed: **Aug. 18, 2021**

(57) **CLAIM**

The ornamental design for a cryptocurrency password notebook page, as shown and described.

DESCRIPTION

The sole FIGURE shows a front view of a page of a cryptocurrency password notebook.

The outermost dashed broken lines in the figure shows a page boundary, and form no part of the claimed design. The other dashed broken lines in the figure depict environment and portions of the article that form no part of the claimed design.

1 Claim, 1 Drawing Sheet
